BOX STRUCTURE

Charles H. Ballard, Marion, Ind., assignor to
 Lindley Box & Paper Company, Marion, Ind., a
 corporation

Application December 28, 1936, Serial No. 117,867

6 Claims. (Cl. 229—31)

This invention relates to a double wall box of card board or like material.

The chief object of this invention is to provide a double wall box of the general character hereinbefore indicated, with bottom engaging flap extensions on each of the inner walls and which have the adjacent ends of said flap extensions lockingly associated together so that when assembled and set up the box will retain itself in box formation.

The general type of box which is old in the art, consists of a single blank arranged to form a central body portion, two outside side walls and two outside end walls, each outside wall having a scored or creased connection with the body portion. Each outside wall has a scored connection with an inside wall and the creasing or scoring is of the same character and in the same direction.

Each inside wall supports a flap extension, the same being connected thereto by a creased or scored connection, which is oppositely directed with reference to the two foregoing scored connections, and the width of these extensions, that is, from its inside wall connected portion to its substantially parallel edge portion, may be that desired.

At the corner between adjacent outside walls, is a corner structure having a diagonal fold at 45° to the creased or scored connections of the corner structure with the adjacent outside walls, the diagonal fold or crease being oppositely directed with respect to the two last mentioned corner structure creases.

If, as and when desired, one pair of opposite inside walls may have lateral flap extensions at each side edge thereof and the same may have a creased or scored connection with the supporting inside wall and have an area and outline less than and within the area and outline of the adjacent corner connection. The inner walls having the lateral flap extensions, are adhesively secured to the supporting outside walls at some distance from the connection of the outside wall to the body portion and in the present instance, the adhesive connection is continued and secures the lateral flap extension to the corner connection.

The foregoing constitutes a description or definition of the type of box in which the present invention is incorporated. The invention relates to the locking arrangement between the respective flap extensions which register with the body and in most instances, constitute the sole locking arrangement embodied in the box.

In the drawing, only one corner of a box embodying the invention is illustrated and also one

corner of the blank therefor, it, of course, being understood that the box has interlocking connections at all four corners and since there are four connections herein illustrated, all four may be embodied in a quadrilateral outlined box, one at each corner or all corners may have like locking connections or diagonally opposite corners may be of like locking form, while intermediate diagonal corners may be of dissimilar form, the intermediate corners being dissimilar or like in character as desired.

The full nature of the invention will be understood from the accompanying drawing and the following description and claims:

In the drawing, Fig. 1 is a perspective view looking down into a corner of a box of the character described and illustrating one form of locking connection.

Fig. 2 is a plan view of the corner portion of the blank from which the corner structure shown in Fig. 1 is obtained.

Fig. 3 is a view similar to Fig. 1 and of a modified form of the invention.

Fig. 4 is a view similar to Fig. 2 and of the form of the invention shown in Fig. 3.

Fig. 5 is a perspective view of a further modified form of the invention and is similar to Figs. 1 and 3.

Fig. 6 is a view similar to Figs. 2 and 4 and of a portion of the blank from which the corner structure shown in Fig. 5 may be obtained.

Fig. 7 is a perspective view similar to Figs. 1, 3 and 5 and of still a further modified form of the invention.

Fig. 8 is a plan view of a portion of the blank from which the form of the invention shown in Fig. 7 is obtained and said view is similar to Figs. 2, 4 and 6.

In Figs. 1 and 2 of the drawing, the simplest form of the invention is illustrated. In these figures, 10 indicates the body portion of the blank, 11 what herein is arbitrarily termed an end wall having a creased connection 12 with the body portion. 13 indicates what is arbitrarily termed a side wall having a creased or scored connection 14 with the body portion. A corner connection 15 has a diagonal fold 16 extending from the intersections of creases 12 and 14 and the latter are continued as at 17 and 18, respectively. Walls 11 and 13 are outer walls.

Hingedly connected as by the creased line 19 is an inner wall or inner end 20 and hingedly connected thereto is a body engaging flap extension 21, the same having the hinged or creased connection 22 therein which is oppositely directed

with respect to creases 12 and 19. Similarly, the outer side wall has hingedly connected to it as at 23 an inner side wall 24 and hingedly connected to the opposite edge thereof as at 25 is 5 a body engaging flap extension 26. The crease or score connection 25 is oppositely directed with reference to the creased or scored connections 14 and 23.

Herein the inside side wall 24 at its free edge 10 has connected to it a lateral flap extension 27 which is hingedly connected thereto by crease or score line 28. The corner connection 15 and the lateral flap extension 27 are separated from each other as indicated at 29.

15 It is to be understood in the production of these boxes, the blank is cut from card board or stock which may come from sheets, a roll, or the like, and after being completely formed as an entirety, Fig. 2 representing only a corner 20 20 portion of such a blank, the blank is fed through a pasting portion of the apparatus which applies thereto a continuous strip of adhesive 30 intermediate the crease or score lines 25 and 23. This continuous strip of adhesive is continued into 25 and across the flap extension, or extensions, 27 as shown. Following this application of adhesive, the blank is engaged by turning mechanisms which turn the inside side walls with their flap extensions inwardly and after being turned inwardly, the blank, with portions infolded in overlapped relation as thus described, is continued into a pressure portion of the apparatus which insures the adhesive connection between the inside side wall and the outside side wall and the 30 corner connection and the lateral flap extension. 35

The invention also contemplates the alternative application of the continuous strip of adhesive between score or crease lines 14 and 23, as indicated at 30a herein, in which event, flaps 40 15 are covered. When thus positioned, one set up operation is eliminated, for opening the side walls draws upwardly and inwardly the folded corners and outer end walls.

The blanks are then assembled in piles and 45 shipped to the ultimate user who sets up the blank into box formation with the minimum of effort, to-wit, the two adhesively secured side walls are turned substantially at right angles to the body portion. Then the two corner connections at one end are infolded upon themselves at 50 the same time being positioned inwardly toward each other and with the bringing up of the outside intermediate or end wall. When thus positioned, the inside end wall is infolded over the 55 lateral flap extensions and the diagonally folded corner connections until the end flap extension engages the body portion. Then the inside end wall is drawn toward the outer end wall until the folded corner connections and lateral flap extensions and the interior of the outside end wall 60 is engaged. Thereupon the flap extension on the end wall automatically interlocks with the adjacent end of the side wall flap extension. After one end of the box is set up, the box may be turned end for end and the other end similarly set up. This completes the box. This may 65 constitute either a cover or a bottom. The blanks for the cover or lid boxes generally are slightly larger than the blanks for the bottom boxes, it being understood one cover or lid box 70 is telescoped over one bottom box to form a complete box.

All of the foregoing, except for the interlocking 75 relation between the body engaging flap extensions, is common to the art.

In Figs. 1 and 2, the simplest form of the invention is illustrated. In this form of the invention, the flap extension 26 is of substantially the full length of the inside side wall and the width is that desired or found convenient. The flap 5 extension 21 of the inside end wall is of any desired width but as to its length, it is appreciably less than that of its supporting wall, being reduced at each end as indicated at 31 by an amount equal to the width of the flap extension 10 26.

In the form of the invention shown in Figs. 1 and 2, lateral displacement or the tendency of the inner ends to open inwardly and upwardly is prevented by the edge 32 engaging the edge 33 15 of the inner side wall flap extension 26.

In Figs. 3 and 4 a further form of the invention is illustrated and in said figures similar numerals of the one hundred series indicate like or similar parts. In this form of the invention, however, the notching of the end flap extension is not provided. In place thereof, a modified form of interlock is obtained, the inside side wall flap 126 including, adjacent the end 133, a substantially parallel slit at 136 and a portion of the crease 125 is slit as at 137. If desired the slit 136 may extend as shown, see Fig. 4, slightly into the inside side wall. In this form of the invention, the end flap extension 121 has a length substantially the same as the inside end wall 120 30 and the outside end wall 111. As shown clearly in Fig. 3, the end flap extension 121 overlies the adjacent end of the side wall flap extension 126 and a portion of the outer edge 138 near the corner of the end flap 121 seats in the slit 136. The 35 slit 137 permits the flap 126 to be depressed at the slotted end to facilitate the aforesaid locking connection. It will be apparent that as to this form of the invention, the lock is solely between the body engaging flap extensions. 40

In Figs. 5 and 6, a modified form of the illustration is illustrated. In this form a slightly different and more complicated arrangement is illustrated and herein numerals of the two hundred series indicate like or similar parts, similar 45 to those indicated by the one hundred series in Figs. 3 and 4 or by the primary series in Figs. 1 and 2. In this form of the invention, in place of the slit 137, the same is enlarged into the flap extension and is illustrated as a slot or notch 237. 50 50 It being understood that in the claims, the term "slit" is sufficiently inclusive to include a slit of any width, thus including a slot.

In this form of the invention also, the end flap extension 221, instead of being foreshortened 55 as shown by the notched arrangement in Figs. 1 and 2 or being of end wall equivalent length as shown in Figs. 3 and 4, is extended as at 234. Also in this form of the invention, the creased line 225, instead of being a substantially straight 60 line adjacent each end at a slight distance therefrom, is slightly biased as indicated by numeral 240, and the termination of the biased crease is coincident with the slot 237. Also, in this form of the invention, at the junction between parallel 65 crease 225 and the biased portion 240, there is provided a transverse slit 241 which extends transversely across the crease 225 and into the inner side wall a slight distance and into the inner side wall flap extension 226 a considerable 70 distance but does not extend completely across the same.

Reference will now be had to Fig. 5. This slit 75 241 is effective to remove any bulge that might be incident to the setting up of the box and the 75

locking of the parts in box relationship. Also, in this form of the invention, the projecting tongue 234, as it were, extends into the notch or slot 237 and the edge portion 238 of the portion 221 will engage the rear end of the slot 237 as at 242 and prevent inward and upward movement of the locking end flap 221. The slit 236 also permits the end of the side wall flap to be depressed to insure reception of the tongue 234 into the notch 0 or slot 237.

Figs. 7 and 8 illustrate a modified form of the invention and numerals of the three hundred series designate like or similar parts, similar to the same parts previously set forth and identified 5 in Figs. 1 and 2 by the primary series of numbers, in Figs. 3 and 4 by the one hundred series and in Figs. 5 and 6 by the two hundred series. In this form of the invention, however, the slit 337 is shown as not only being formed in the 0 side wall flap extension 326 but the same is extended into the inner side wall 324 and the flap extension 327 is correspondingly reduced as at 344. If desired, the slit 341 may be provided. This is clearly shown in Fig. 7. If desired, al- 5 though the same is not illustrated herein, the slit indicated by the numeral 241 in Figs. 5 and 6, and by 341 in Figs. 7 and 8, may also be applied to the form of the invention shown in Figs. 3 and 4. In the form of the invention illustrated 10 in Figs. 7 and 8, the end extension includes the locking tongue 334 with the locking edge 338, similar to the formation illustrated in Figs. 5 and 6. If desired, crease 325 may be biased similar to portion 240 of crease 225. The notch 337 in the side wall permits portion 334 to be of greater length, that is, projects laterally of the end wall to a greater extent than portion 234. The side edges in each instance may frictionally engage the immediately exposed side wall, although the same is not necessary for interlocking, merely increasing the effectiveness thereof.

While the invention has been described in great detail in the foregoing specifications, the same is to be considered as illustrative and not restrictive in character. It is to be understood also that with the exception of the form of the invention shown in Figs. 7 and 8, the interlocking arrangement is obtained solely through the interlocking association of the body engaging flap extensions upon the inside walls. The various modifications which have been illustrated and described herein, as well as those suggested herein, as well as others which will readily suggest themselves to persons skilled in this art, are all considered to be within the broad scope of this invention, reference being had to the appended claims.

The invention claimed is:

1. A corner construction for a knockdown single blank box having a body and adjacent double walls with a diagonally foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box formation, the junction between one flap extension and its supporting wall being slit a length at least equal to the width of the adjacent flap extension, and by the addition of a slit angular to the first mentioned slit and extending therefrom into the first mentioned flap extension.

2. A corner construction for a knockdown

single blank box having a body and adjacent double walls with a diagonal foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box formation, the junction between one flap extension and its supporting wall being slit a length at least equal to the width of the adjacent flap extension, and by the addition of a slit angular to the first mentioned slit and extending therefrom into the first mentioned flap extension, the slit separated wall and flap having another and bulge removing slit therein adjacent but spaced from the angularly positioned slit and angular to the foldable connection therebetween.

3. A corner construction for a knockdown single blank box having a body and adjacent double walls with a diagonally foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box formation, the junction between one flap extension and its supporting wall being slit a length at least equal to the width of the adjacent flap extension, and by the addition of a slit angular to the first mentioned slit and extending therefrom into the first mentioned flap extension, the foldable connection between the slit separated wall and flap including a slightly angularly directed portion immediately adjacent the second mentioned slit.

4. A corner construction for a knockdown single blank box having a body and adjacent double walls with a diagonally foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box formation, the junction between one flap extension and its supporting wall being slit a length at least equal to the width of the adjacent flap extension, and by the addition of a slit angular to the first mentioned slit and extending therefrom into the first mentioned flap extension, the slit separated wall and flap having another and bulge removing slit therein adjacent but spaced from the angularly positioned slit and angular to the foldable connection therebetween, and the foldable connection including a slightly angularly directed portion immediately adjacent the second mentioned slit and terminating substantially at the bulge removing slit.

5. A corner construction for a knockdown single blank box having a body and adjacent double walls with a diagonally foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box formation, the junction between one flap extension and its supporting wall being slit a length at least equal to the width of the adjacent flap extension, and

by the addition of a slit angular to the first mentioned slit and extending therefrom into the first mentioned flap extension, the junction slit being of appreciable width and constituting a slot.

- 5 6. A corner construction for a knockdown single blank box having a body and adjacent double walls with a diagonally foldable corner integral with adjacent outer wall portions thereof and independent body overlapping flap extensions on adjacent inner walls, including in combination an interlocking connection between adjacent ends of adjacent flap extensions and constituting the sole locking arrangement between the walls for retaining the same in box forma-

tion, the junction between one flap extension and its supporting wall being slit a length at least equal to the width of the adjacent flap extension, and by the addition of a slit angular to the first mentioned slit and extending therefrom into the 5 first mentioned flap extension, the slit separated wall and flap having another and bulge removing slit therein adjacent but spaced from the angularly positioned slit and angular to the foldable connection therebetween, the junction slit 10 being of appreciable width and constituting a slot.

CHARLES H. BALLARD.
